UNITED STATES PATENT OFFICE.

REA A. DIETTERICH, OF SCRANTON, PENNSYLVANIA.

DESIGN FOR A CLOTHES-LINE HOLDER.

45,988.

Specification for Design.

Patented June 23, 1914.

Application filed December 30, 1913. Serial No. 809,585. Term of patent 7 years.

To all whom it may concern:

Be it known that I, REA A. DIETTERICH, a citizen of the United States, residing at Scranton, in the county of Lackawanna and State of Pennsylvania, have invented a new, original, and ornamental Design for a Clothes-Line Holder, of which the following is a specification, reference being had to the accompanying drawing, forming part thereof.

The figure is a perspective view of the clothes line holder, showing my new design.

I claim:—

The ornamental design for a clothes line holder, as shown.

REA A. DIETTERICH.
